UNITED STATES PATENT OFFICE

95,272

DESIGN FOR A STOVE

Henry Lange, Quincy, Ill., assignor to The Quincy Stove Manufacturing Company, Quincy, Ill., a corporation of Illinois

Application February 16, 1935, Serial No. 55,470

Term of patent 14 years

To all whom it may concern:

Be it known that I, Henry Lange, a citizen of the United States, residing at Quincy, in the county of Adams and State of Illinois, have invented a new, original, and ornamental Design for a Stove, of which the following is a specification, reference being had to the accompanying drawing, forming a part thereof,

The drawing is a perspective view showing my new design.

I claim:

The ornamental design for a stove as shown.

HENRY LANGE.
